DOUBLE IMPELLER IMPACT BREAKER

Norman H. Kessler and Hans I. Hansen, Cedar
Rapids, Iowa, assignors to Lee H. Kessler,
Springville, N. Y.

Application August 3, 1950, Serial No. 177,527

2 Claims. (Cl. 241—80)

1

The present invention relates to impact breakers and more particularly to the improvement in a double impeller impact breaker of the type having the impellers arranged in a side by side relation.

In the fabrication of aggregates or the crushing of ores or rock products, it is important to be able to control the crushed material gradation or to compensate for an over or undersupply of fines or for an off-gradation of one of the sizes in the specification. An object of our invention is to provide a simplified construction of such controlling means and more particularly to provide means for the adjustment of the relative location of the impellers in a plane parallel to a plane passing through the centerline of the two impeller shafts.

Another object is to provide an adjustment of the end spacing between the impeller impact blades of the two impellers from approximately half an inch to approximately six inches in order to control the baffling of the downward moving material.

Still another object of our invention is to provide an end spacing between the impeller blades of the two impellers of slightly less than the maximum size required by an aggregate specification in order to avoid further reduction of material already meeting the specification and in order to increase the output of the breaker and to decrease the wear of the wearing members.

Other features and advantages of our invention will become apparent to those skilled in the art upon consideration of the accompanying drawings and the following specification, wherein is disclosed an embodiment of our invention with the understanding however, that our description and drawings are illustrative and diagrammatic in a broad sense and that changes in disposition and number of parts may be made without departing from the spirit of the invention. We therefore do not wish to be limited specifically to the device herein shown except to the extent as fall within the scope of the appended claims.

In said drawings:

Fig. 1 is a side view of a double impeller impact breaker constructed in accordance with the teachings of the present invention;

Fig. 2 is part of a transverse sectional view thereof, as on line 2—2, Fig. 1;

Fig. 3 is a fragmentary side view showing the impeller adjusting means taken on line 3—3, Fig. 2;

Fig. 4 is an enlarged fragmentary side view of the lower right hand side of the machine;

2

Fig. 5 is a horizontal section taken substantially on line 5—5, Fig. 4;

Fig. 6 is a transverse vertical section taken on line 6—6, Fig. 4.

Referring now to the drawings; since the breaker itself is well known to those familiar with the art, it is described in a few details only, sufficiently to support the novel features of our invention, which will be distinctly pointed out and 10 more fully described as this specification proceeds.

In Fig. 1, 10 indicates a pair of spaced supporting members between which the breaker housing 11 is mounted. The breaker housing 11 is lined 15 throughout with abrasion resistant liner 12 as is the case with equipment of this type, in order to minimize the wear due to the action of the breaker during operation. An inlet or feed opening 13 is provided at the upper end of the breaker 20 housing 11, a suitable feed chute 14 is mounted over the feed opening 13 for the introduction of the rock or ore to be impacted. The round impact bars 15 are disposed at both ends of the breaker housing 11 in a spaced relation with the 25 ends and with one another, symmetrically around a plane passing through the centerline of the housing and perpendicular to the spaced supporting members 10. The three lower impact bars 15 are adjustable in a horizontal direction by means of the bolt 16. The two impellers 17 are rotatably mounted, crosswise in an adjustable, spaced relation in the breaker housing 11, supported in the pillow blocks 18 and on the 30 spaced supporting members 10. Below the impellers 17 is provided a discharge opening 19 for the discharge of the impacted rock or ore, which has passed downward in the space between the impact bars 15 and the ends of the breaker housing 11 or downward in the adjustable space between the impellers 17.

Referring now to Fig. 2, in the impellers 17 is inserted and held in place, parallel to their centerlines, impeller blades 20, three in each impeller, evenly spaced. The ends of the impeller shafts 21 extend through the pillow blocks 18 accommodating the necessary sheaves for the standard prime mover, for the rotation of the impellers in such a direction, that the impeller blades 20 travel upward in a plane located 45 between the impellers 17. The standard prime movers are not shown or described, assuming that any known unit may be utilized.

Referring now in particular to Fig. 3 considering the novel features of the adjustable means 50 for controlling the end to end clearance of the

impeller blades 20, the impeller shafts 21 onto which the impellers 17 are keyed are rotatably mounted in the pillow blocks 18 as previously described. The supporting members 10 are provided with multiple slots 23 for adjustable clamping engagement of the pillow blocks 18, the through-bolts 24, and the clamping plates 25, the pillow blocks and clamping plates having holes matching the slots. On either side the pillow blocks, perpendicular to the supporting members 10, and in a spaced relation, providing for adjustment of the pillow blocks 18 is welded a gusset 22. Each gusset is provided with two laterally spaced openings 26 for threaded engagement with adjusting bolt 27 and locking means 28. In the edge of the supporting members 10 and the pillow blocks 18 are vertical lines 29, indicating the lower limit of approximately $\frac{1}{2}$ " of the end to end clearance of the impeller blades 20, the maximum limit of approximately 6" spacing can be measured from these lines or a plate or other means with a scale and a pointer can be mounted as a help for getting the proper and desired location of the pillow blocks with the corresponding end spacing of the impeller blades.

From the foregoing, it will be seen, that we have provided a novel form of a double impeller impact breaker and especially a novel form of an adjustable mounting and adjustment of the impellers and the end to end clearance between the impeller blades.

In order to get a better and more complete understanding of the operation of the double impeller impact breaker and of our invention the following will describe the operation of the unit as utilized in a distinct method of impacting rock or ore with a controlled baffling of the downward moving material taking full advantage of the adjustment of the end to end clearance of the impeller blades.

After the primary blasting of the rock or ore to be impacted, it is transported to the double impeller impact breaker by the usual means and deposited at the feed opening. The rock or ore is then introduced into the breaker through the feed opening on top of the housing utilizing an apron feeder or other means. Dropping from the feed opening towards the impellers, spaced crosswise in the breaker housing and rotating at a high speed in opposite direction with the impeller blades moving upwards in a plane between the impellers, the rock or ore is impacted repeatedly, propelled upwards and impacted against the rock being fed into the breaker or against the spaced breaker bars. Finally the rock or ore is discharged through the discharge opening below the impellers. Should a check on the discharged material indicate a gradation outside the specification the end to end clearance of the impeller blades is adjusted, allowing more or less, as the case may be, of the material to pass downward between the impellers without being impacted.

What we claim is:

1. A stone breaker, comprising spaced supporting members, a casing mounted thereon de-

fining a breaker chamber for the introduction of the stone to be reduced and for the discharge of the reduced stone, impellers having impact blades thereon disposed in opposing side by side relation in the lower portion of said casing-chamber and spaced from the end walls of the casing, a series of spaced impact bars above the impellers and disposed along the end walls of the casing in spaced relation thereto, adjustable pillow blocks for said impellers mounted on said supporting members, means applied to said members and operatively engageable with opposite sides of the pillow blocks for adjusting the impellers toward and from each other for varying the end to end clearance between the opposing impeller blades in a plane parallel to a plane passing through the center lines of the impellers, and means adjustably mounted on said casing adjacent the end walls thereof for movement horizontally toward and from the companion impellers and having spaced impact bars thereon disposed in the spaces between the impellers and the casing walls and constituting a continuation of said series of impact bars.

2. In a rock crushing apparatus, a casing defining a breaking chamber having upper and lower openings therein for the introduction of the stone to be reduced and for the discharge of the reduced stone, a pair of bladed impellers disposed in side by side relation in the lower portion of said chamber in spaced relation to the end walls thereof, means operatively connected to said impellers for adjusting the end to end clearance between the blades thereof in a plane parallel to a plane passing through the center line of the impellers, impact bars disposed immediately over the impellers at opposite sides of the vertical plane between the impellers, a series of vertically-spaced impact bars paralleling the end walls of the casing in spaced relation thereto and to said bars over the impellers and extending upwardly from a point substantially opposite said last-named bars to the top of the casing, means adjustably mounted on said casing adjacent the end walls thereof for movement horizontally toward and from the companion impellers and having spaced impact bars thereon disposed in the spaces between the impellers and the casing walls and constituting a continuation of said series of impact bars.
